LINEAR POWER SUPPLY CIRCUIT

CROSS-REFERENCE TO RELATED
APPLICATIONS

This nonprovisional application is a continuation application of International Patent Application No. PCT/JP2022/006584 filed on Feb. 18, 2022, which claims priority Japanese Patent Application No. 2021-034178 filed in Japan on Mar. 4, 2021, the entire contents of which are hereby incorporated by reference.

BACKGROUND OF THE INVENTION

1. Technical Field

The invention disclosed herein relates to linear power supply circuits.

2. Description of Related Art

Linear power supply circuits such as those of an LDO (low-dropout) type are used as power supplies in a variety of devices.

With linear power supply circuits, it is preferable that, even with a reduced capacitance value in the output capacitor, phase compensation be possible without a great increase in the circuit area.

An example of known technology relevant to what has been mentioned above is seen in JP-A-2020-071681.

The known linear power supply circuit includes an input terminal T1, an output terminal T2, a first output transistor 1, a driver 2, a reference voltage generator 3, and a phase compensation circuit 8. It also has an output capacitor 6 and a load 7 externally connected to it. The linear power supply circuit bucks (steps-down) an input voltage VIN to generate an output voltage VOUT and supplies the output voltage VOUT to the load 7. The conductivity of the first output transistor 1, and also that of a second output transistor 81, which will be described later, (put otherwise, their on-resistance values) are controlled with a gate signal G1. In the configuration shown in FIG. 10, the first and second output transistors 1 and 81 are implemented with PMOSFETs (P-channel MOSFETs). Accordingly, as the voltage level of the gate signal G1 decreases, the conductivities of the first and second output transistors 1 and 81 increase and the output voltage VOUT rises.

The driver 2 includes a differential amplifier 21, a capacitance 22, a PMOSFET 23, a current amplifier 24, and a PMOSFET 25 provided in a current mirror circuit.

One terminal of the capacitance 22 is fed with the output of the differential amplifier 21, and the other terminal of the capacitance 22 is fed with a ground potential. Thus the connection node between the differential amplifier 21 and the capacitance 22 is earth-grounded in a high-frequency band, and this helps achieve fast response of the driver 2.

The phase compensation circuit 8 includes a second output transistor 81, a resistor 82, and a capacitor 83.

One terminal of the resistor 82 is connected to the gate of the first output transistor 1 and to the gate of the PMOSFET 25 provided in the current minor circuit, and the other terminal of the resistor 82 is connected to the gate of the second output transistor 81. The capacitor 83 is connected between the gate and the source of the second output transistor 81.

Now, a description will be given of the function of the phase compensation circuit 8 in the linear power supply

2

circuit shown in FIG. 10 as an example of known technology. FIG. 11 is a diagram showing the gain response of the transfer function of the first output transistor 1 and the phase compensation circuit 8. A first pole frequency FP1' is the frequency of a first pole that is ascribable to a parasitic capacitance CPD. The first pole of the transfer function of the first output transistor 1 is a pole with which the output capacitor 6 is unrelated.

A current that passes through the second output transistor 81, which has a CR circuit (the resistor 82 and the capacitor 83) connected to its gate, causes the first pole frequency FP1' to shift to a lower range as compared with in a case where the phase compensation circuit 8 is not provided (thick broken line). This results in a lower gain in a range higher than the first pole frequency FP1' as compared with in a case where the first pole frequency FP1' does not shift to a lower range.

Moreover, due to the first and second output transistors 1 and 81 being connected in parallel with each other and the first output transistor 1 not being affected by the resistor 82, a second pole appears at the original position of the first pole frequency FP1' before its shifting to a lower range, the frequency at the second pole being the second pole frequency FP2'. The shift of the first pole frequency FP1' to a lower range and the resulting drop in the gain causes the zero-cross frequency FZC' to shift to a lower range.

The first and second pole frequencies FP1' and FP2' are related to the second pole frequency of the transfer function 30 of the linear power supply circuit and the output capacitor 6 shown in FIG. 10. Thus the phase compensation circuit 8 can shift the second pole frequency of the transfer function of the linear power supply circuit and the output capacitor 6 shown in FIG. 10 to a lower range as compared with in a case where the phase compensation circuit 8 is not provided. The shift permits the phase compensation circuit 8 to reduce, in a range higher than the second pole frequency of the transfer function of the linear power supply circuit and the output capacitor 6 shown in FIG. 10, the gain of the transfer function of the linear power supply circuit and the output capacitor 6 shown in FIG. 10 as compared with in a case where the phase compensation circuit 8 is not provided. This results in the zero-cross frequency of the transfer function of the linear power supply circuit and the output capacitor 6 shown in FIG. 10 shifting to a lower range. Thus, the linear power supply circuit shown in FIG. 10 can, even with a reduced capacitance in the output capacitor 6, achieve phase compensation with the sole addition of the phase compensation circuit 8 (i.e., without a great increase in the circuit area).

BRIEF DESCRIPTION OF THE DRAWINGS

FIG. 1 is a diagram showing one configuration example of 55 a linear power supply circuit according to a first embodiment.

FIG. 2 is a diagram showing one configuration example of an operational amplifier.

FIG. 3 is a diagram showing one configuration example of 60 a current amplifier.

FIG. 4 is a diagram showing a relationship, in the linear power supply circuit shown in FIG. 1, among the gate voltages of a first and a second output transistor and the output voltage.

FIG. 5 is a diagram showing a configuration example of 65 a linear power supply circuit according to a second embodiment.

FIG. 6 is a diagram showing another configuration example of a current amplifier.

FIG. 7 is a diagram showing a configuration example of a linear power supply circuit according to a third embodiment.

FIG. 8 is an exterior view of a semiconductor integrated circuit device.

FIG. 9 is an exterior view of a vehicle.

FIG. 10 is a diagram showing one configuration example of a linear power supply circuit according to JP-A-2020-071681.

FIG. 11 is a diagram showing the gain response of the transfer function of the linear power supply circuit and the output capacitor shown in FIG. 10.

DETAILED DESCRIPTION

In the present description, a constant voltage denotes a voltage that is constant under ideal conditions and may be a voltage that can vary slightly with change in temperature and the like.

In the present description, a reference voltage denotes a voltage that is constant under ideal conditions and may be a voltage that can vary slightly with change in temperature and the like.

In the present description, a constant current denotes a current that is constant under ideal conditions and may be a current that can vary slightly with change in temperature and the like.

In the present description, a MOSFET denotes a transistor of which the gate has a structure composed of at least three layers which are: a layer of a conductor or a semiconductor with a low resistance value such as polysilicon; a layer of an insulator; and a layer of a P-type, N-type, or intrinsic semiconductor. That is, a MOSFET may have any gate structure other than a three-layer structure of metal, oxide, and semiconductor.

First Embodiment

FIG. 1 is a diagram showing one configuration example of a linear power supply circuit according to a first embodiment. The linear power supply circuit shown in FIG. 1 includes an input terminal T1, an output terminal T2, a first output transistor 1, a driver 2, a reference voltage generator 3, resistors 4 and 5, and a phase compensation circuit 8. The linear power supply circuit also has an output capacitor 6 and a load 7 externally connected to it.

The first output transistor 1 is provided between the input terminal T1, to which the input voltage VIN is applied, and the output terminal T2, to which the output voltage VOUT is applied.

The driver 2 drives the first output transistor 1 and a second output transistor, which will be described later. Specifically, the driver 2 feeds a gate signal G1 to the gate of the first output transistor 1 and via the resistor 82 to the gate of the second output transistor 81, thereby to drive the first and second output transistors 1 and 81. The conductivities of the first and second output transistors 1 and 81 (put otherwise, their on-resistance values) are controlled by the gate signal G1. In the configuration shown in FIG. 1, the first and second output transistors 1 and 81 are implemented with PMOSFETs. Accordingly, as the voltage level of the gate signal G1 decreases, the conductivities of the first and second output transistors 1 and 81 increase and the output voltage VOUT rises. Put the other way around, as the voltage level of the gate signal G1 increases, the conduc-

tivities of the first and second output transistors 1 and 81 decrease and the output voltage VOUT falls. The first and second output transistors 1 and 81 may be implemented with, instead of PMOSFETs, NMOSFETs or bipolar transistors.

The driver 2 includes a differential amplifier 21, a capacitance 22, a PMOSFET 23, a current amplifier 24, and a PMOSFET 25.

The inverting input terminal (−) of the differential amplifier 21 is fed with a feedback voltage VFB, and the non-inverting input terminal (+) of the differential amplifier 21 is fed with a reference voltage VREF. Based on the difference ΔV (=VFB-VREF) between the feedback voltage VFB and the reference voltage VREF, the driver 2 drives the first and second output transistors 1 and 81. As the difference ΔV increases, the driver 2 raises the voltage level of the gate signal G1; as the difference ΔV decreases, the driver 2 lowers the voltage level of the gate signal G1.

One terminal of the capacitance 22 is fed with the output of the differential amplifier 21, and the other terminal of the capacitance 22 is fed with the ground potential.

The source of the PMOSFET 23 is fed with the output voltage VOUT, and the gate of the PMOSFET 23 is fed with a voltage based on the output of the differential amplifier 21 (i.e., the voltage at the connection node between the differential amplifier 21 and the capacitance 22). The PMOSFET 23 converts the voltage based on the output of the differential amplifier 21 into a current to output this current from its drain. The connection node between the differential amplifier 21 and the capacitance 22 is earth-grounded in a high-frequency band, and this helps achieve fast response of the driver 2.

The withstand voltage of the differential amplifier 21 and the PMOSFET 23 is lower than the withstand voltage of the current amplifier 24. The gain of the differential amplifier 21 is lower than the gain of the current amplifier 24. This helps reduce the size of the differential amplifier 21 and the PMOSFET 23.

The current amplifier 24 amplifies the current I_a output from the drain of the PMOSFET 23. The supply voltage for the current amplifier 24 is a constant voltage VREG. That is, the current amplifier 24 operates from the voltage between the constant voltage VREG and the ground potential.

The PMOSFET 25 along with the first output transistor 1 constitutes a current mirror circuit. The PMOSFET 25 converts the current I_b output from the current amplifier 24 into a voltage to feed this voltage to the gate of the first output transistor 1.

The reference voltage generator 3 generates the reference voltage VREF. The resistors 4 and 5 generate the feedback voltage VFB as a division voltage of the output voltage VOUT.

The output capacitor 6 and the load 7 are supplied with the output voltage VOUT from the output terminal T2.

The phase compensation circuit 8 includes a second output transistor 81, a resistor 82, a capacitor 83, and an operational amplifier 84. Incidentally, a configuration where a delay can occur between the gate potentials of the first and second output transistors 1 and 81 permits omission of the resistor 82 and the capacitor 83 as distinct from the configuration of this embodiment.

The second output transistor 81 is connected in parallel with the first output transistor 1. That is, the source of the second output transistor 81 is connected to the source of the first output transistor 1, and the drain of the second output transistor 81 is connected to the drain of the first output transistor 1. In this embodiment, the size of the second

output transistor **81** is larger than the size of output transistor **1** so that the current through the second output transistor **81** is higher than the current through the first output transistor **1**. Here, "size" specifically is "area."

One terminal of the resistor **82** is connected to the gates of the first output transistor **1** and the PMOSFET **25**, and the other terminal of the resistor **82** is connected to the gate of the second output transistor **81**.

The capacitor **83** is provided between the gate and the source of the second output transistor **81**. In this embodiment, the parasitic capacitor of the second output transistor **81** is used as the capacitor **83**. Instead, a capacitor other than the parasitic capacitor of the second output transistor **81** may be used as the capacitor **83**, or the parasitic capacitor of the second output transistor **81** along with a capacitor other than the parasitic capacitor of the second output transistor **81** may be used as the capacitor **83**. Using a capacitor other than the parasitic capacitor of the second output transistor **81** as part of the capacitor **83** permits easy adjustment of the capacitance value of the capacitor **83**. It is preferable that the capacitance value of the capacitor **83** be higher than the capacitance value of the parasitic capacitance CPD. The phase compensation circuit **8** may further include a capacitance provided between the gate and the drain of the second output transistor **81**.

The operational amplifier **84** is one example of a potential difference suppressor that suppresses a potential difference between the gates of the first and second output transistors **1** and **81**. The potential difference suppressor can be configured, for example, to monitor the voltage difference between the voltages at the gates of the first and second output transistors **1** and **81** and, if the voltage difference is equal to or larger than a predetermined value, output a control signal to control at least one of the voltages at the gates of the first and second output transistors **1** and **81** so as to reduce the potential difference between the gates of the first and second output transistors **1** and **81**. In this embodiment, the operational amplifier **84** outputs the just-mentioned control signal.

The operational amplifier **84** has an input offset voltage **84A**. The non-inverting input terminal (+) of the operational amplifier **84** is connected to the gate of the first output transistor **1**. The inverting input terminal (-) and the output terminal of the operational amplifier **84** are connected to the gate of the second output transistor **81**. With this configuration, if the potential difference between the gates of the first and second output transistors **1** and **81** becomes equal to or higher than the input offset voltage **84A**, the operational amplifier **84** operates to keep the potential difference between the gates of the first and second output transistors **1** and **81** equal to the input offset voltage **84A**.

FIG. 2 is a diagram showing one configuration example of the operational amplifier **84**. The operational amplifier **84** of the configuration example shown in FIG. 2 includes an NMOSFET **841** as a first input differential pair transistor, an NMOSFET **842** as a second input differential pair transistor, PMOSFETs **843** and **844** constituting a current mirror circuit, and an NMOSFET **845** serving as a source-follower output stage.

The current minor circuit mentioned above feeds the NMOSFET **841** with a first current and feeds the NMOSFET **842** with a second current as the minor current of the first current.

The source of the NMOSFET **841** serves as the non-inverting input terminal (+) of the operational amplifier **84**, the source of the NMOSFET **842** serves as the inverting input terminal (-) of the operational amplifier **84**, and the

source of the NMOSFET **845** serves as the output terminal of the operational amplifier **84**. A bias voltage **Vb** is applied to the gates of the NMOSFETs **841** and **842**. The drain of the NMOSFET **841** is connected to the drain of the PMOSFET **843** and to the gate of the NMOSFET **845**. The drain of the NMOSFET **842** is connected to the drain and the gate of the PMOSFET **844** and to the gate of the PMOSFET **843**. The input voltage **VIN** is fed to the source of the PMOSFET **843**, to the source of the PMOSFET **844**, and to the drain of the NMOSFET **845**. The source of the NMOSFET **845** is connected to the source of the NMOSFET **842**.

In the operational amplifier **84** of the configuration example shown in FIG. 2, the input offset voltage **84A** is generated at least either by giving the NMOSFETs **841** and **842** different channel width-to-channel length ratios or by giving the first and second currents different values (setting the mirror ratio of the above-mentioned current minor circuit to other than one). With this configuration it is easy to set the input offset voltage **84A** exactly to the design value.

FIG. 3 is a diagram showing one configuration example of the current amplifier **24** in the linear power supply circuit shown in FIG. 1. The current amplifier **24** includes current-sink current mirror circuits **CM_1**, **CM_2**, . . . , and **CM_n** and current-source current mirror circuits **CM_3**, . . . , and **CM_n-1** (though **CM_n-1** is not shown in FIG. 2B). Between, at one end, the current-sink current mirror circuit **CN_1** and a constant current source **SC1** that produces a constant current **I1** and, at the other end, the current-sink current mirror circuit **CM_n**, from the input to the output of the current amplifier **24**, there are arranged current-sink current mirror circuits and current-source current mirror circuit alternately so as to amplify a current. The amplified current eventually becomes, in the last stage, the current **Ib** to be converted into a voltage to serve as the gate signal **G1**.

FIG. 4 is a diagram showing the relationship, in the linear power supply circuit shown in FIG. 1, among the input voltage **VIN**, the gate voltages of the first and second output transistors **1** and **81** respectively, and the output voltage **VOUT**. In FIG. 4, the vertical axis represents voltage and the horizontal axis represents time. Thus FIG. 4 shows the variation with time of each of the input voltage **VIN**, the output voltage **VOUT**, the gate voltage **VPG** (gate signal **G1**) that drives the first output transistor **1**, and the gate voltage **VPGF** that drives the second output transistor **81**.

FIG. 4 reveals the following. At time point **t1**, at which the input voltage **VIN** starts to rise from 4.75 V to 16 V, the gate voltages **VPG** and **VPGF** both start to rise and here, with no delay from the rise of the gate voltage **VPG**, the gate voltage **VPGF** rises. That is, the gate voltages **VPG** and **VPGF** rise together. This owes to the operational amplifier **84** suppressing the voltage difference between the gate voltages **VPG** and **VPGF**.

With attention paid to the conductivities of the first and second output transistors **1** and **81** respectively, the suppressed voltage difference between the gate voltages **VPG** and **VPGF** results in a suppressed difference in conductivity between those transistors. This helps suppress an overshoot in the output voltage **VOUT** and prevents the output voltage **VOUT** from exceeding the target output voltage of 5 V too far.

Second Embodiment

FIG. 5 is a diagram showing the configuration of a linear power supply circuit according to a second embodiment. In FIG. 5, such parts as find their counterparts in FIG. 1 are

identified by the same reference signs and for them no detailed description will be repeated.

In this embodiment, the driver 2 includes a differential amplifier 21', a capacitance 22', an NMOSFET 23', a current amplifier 24, and a PMOSFET 25.

The differential amplifier 21' outputs a voltage commensurate with the difference between the feedback voltage VFB and the reference voltage VREF. The supply voltage for the differential amplifier 21' is a first constant voltage VREG1. That is, the differential amplifier 21' operates from the voltage between the first constant voltage VREG1 and the ground potential.

The withstand voltage of the differential amplifier 21' and the NMOSFET 23' is lower than the withstand voltage of the current amplifier 24. The gain of the differential amplifier 21' is lower than the gain of the current amplifier 24. This helps reduce the size of the differential amplifier 21' and the NMOSFET 23'.

One terminal of the capacitance 22' is fed with the output of the differential amplifier 21', and the other terminal of the capacitance 22' is fed with the output voltage VOUT. Instead of the output voltage VOUT, a voltage that depends on the output voltage VOUT may be fed to the other terminal of the capacitance 22'.

The source of the NMOSFET 23' is fed with the gate potential, and the gate of the NMOSFET 23' is fed with a voltage based on the output of the differential amplifier 21' (i.e., the voltage at the connection node between the differential amplifier 21' and the capacitance 22'). The NMOSFET 23' converts the voltage based on the output of the differential amplifier 21' into a current to output this current from its drain. The connection node between the differential amplifier 21' and the capacitance 22' serves as an output voltage VOUT-ground (positive ground) in a high-frequency band, and this helps achieve fast response of the driver 2. The current amplifier 24 amplifies the current I_a output from the drain of the NMOSFET 23'. The supply voltage for the current amplifier 24 is a second constant voltage VREG2. That is, the current amplifier 24 operates from the voltage between the second constant voltage VREG2 and the ground potential. The first and second constant voltages VREG1 and VREG2 may have an equal value, or may have different values. In this configuration example, the current I_a passes from the current amplifier 24 to the NMOSFET 23', and thus the current amplifier 24 can be implemented with, for example, a circuit configuration as shown in FIG. 6.

The phase compensation circuit in the linear power supply circuit of this embodiment shown in FIG. 5 is similar to the one in the linear power supply circuit of the first embodiment shown in FIG. 1. It thus exerts a similar effect to suppress an overshoot in the output voltage VOUT. Moreover, the linear power supply circuit of this embodiment shown in FIG. 5 can ensure the operation of the differential amplifier 21' even with a low set value for the output voltage VOUT. Incidentally, in a case where a low voltage is used as the input voltage VIN, instead of the first constant voltage VREG1 the input voltage VIN can be used as the supply voltage for the differential amplifier 21', and instead of the second constant voltage VREG2 the input voltage VIN can be used as the supply voltage for the current amplifier 24.

Third Embodiment

FIG. 7 is a diagram showing the configuration of a linear power supply circuit according to a third embodiment. The linear power supply circuit shown in FIG. 7 results from

applying the phase compensation circuit 8 to a linear power supply circuit provided with a well-known PMOS source-grounded output stage.

The linear power supply circuit provided with the PMOS source-grounded output stage shown in FIG. 7 is well known as a conventional technology, and therefore no detailed description of it will be given. Also with the linear power supply circuit shown in FIG. 7, it is possible to suppress an overshoot in the output voltage by suppressing a difference in conductivity between the first and second output transistors Q1 and 81.

As described above, a phase compensation circuit according to the invention disclosed herein can be applied not only to the linear power supply circuits according to the first and second embodiments but to configurations that include a plurality of output transistors in general.

Application Example 1

FIG. 8 is an external view of a semiconductor integrated circuit device. The semiconductor integrated circuit device shown in FIG. 8 has external pins P1 to P14 and incorporates an internal power supply 9. The internal power supply 9 is one of the linear power supply circuits according to the first to third embodiments described previously and, in a case where it is incorporated in this way, whether an output capacitor is provided or not does not matter. The internal power supply 9 supplies an internal supply voltage Vreg (i.e., the output voltage VOUT of the linear power supply circuit) to at least some circuits in the semiconductor integrated circuit device shown in FIG. 8.

Application Example 2

FIG. 9 is an external view of a vehicle X. The vehicle X of this configuration example incorporates various electronic devices X11 to X18 that operate by being supplied with a voltage output from an unillustrated battery. For the sake of convenience, in the diagram, the electronic devices X11 to X18 may be shown at places different from where they are actually arranged.

The electronic device X11 is an engine control unit that performs control with respect to an engine (injection control, electronic throttle control, idling control, oxygen sensor heater control, automatic cruise control, etc.).

The electronic device X12 is a lamp control unit that controls the lighting and extinguishing of HID (high-intensity discharged lamps), DRLs (daytime running lamps), or the like.

The electronic device X13 is a transmission control unit that performs control with respect to a transmission.

The electronic device X14 is a movement control unit that performs control with respect to the movement of the vehicle X1 (ABS [anti-lock brake system] control, EPS [electric power steering] control, electronic suspension control, and the like).

The electronic device X15 is a security control unit that drives and controls door locks, burglar alarms, and the like.

The electronic device X16 comprises electronic devices incorporated in the vehicle X1 as standard or manufacturer-fitted equipment at the stage of factory shipment, such as wipers, power side mirrors, power windows, dampers (shock absorbers), a power sun roof, and power seats.

The electronic device X17 comprises electronic devices fitted to the vehicle X1 optionally as user-fitted equipment, such as A/V (audio/visual) equipment, a car navigation system, and an ETC (electronic toll control system).

The electronic device X18 comprises electronic devices provided with high-withstand-voltage motors, such as a vehicle-mounted blower, an oil pump, a water pump, and a battery cooling fan.

Any of the linear power supply circuits described previously can be built into any of the electronic devices X11 to X18.

<Notes>

The embodiments described above are to be taken in every aspect illustrative and not restrictive, and the technical scope of the invention disclosed herein is defined not by the description of the embodiments given above but by the appended claims and is to be understood to encompass any modifications made within a scope equivalent in significance to what is claimed.

The phase compensation circuit may be any circuit that can suppress a delay between the driving signals for transistors connected in parallel with each other, and its circuit configuration is not limited to that of the phase compensation circuit 8, which is described merely as an example.

According to one aspect of what is disclosed herein, a linear power supply circuit includes: an output stage between an input terminal (T1) to which an input voltage is applied and an output terminal (T2) to which an output voltage is applied, the output stage including a first output transistor (1) and a second output transistor (81) connected in parallel with each other; a driver (2) configured to drive the first and second output transistors based on the difference between a voltage based on the output voltage and a reference voltage; and a potential difference suppressor (84) configured to suppress a potential difference between the control terminal of the first output transistor and the control terminal of the second output transistor. (A first configuration.)

The linear power supply circuit of the first configuration described above suppresses a potential difference between the control terminals of the first and second output transistors. It is thus possible to suppress an overshoot in the output voltage caused by a delay ascribable to a resistor and a capacitor for phase compensation.

In the linear power supply circuit of the first configuration described above, the potential difference suppressor may be configured to monitor the voltage difference between the voltage at the control terminal of the first output transistor and the voltage at the control terminal of the second output transistor and, if the voltage difference is equal to or larger than a predetermined value, output a control signal to control at least one of the voltages at the control terminals of the first and second output transistors so as to reduce the potential difference between the control terminals of the first and second output transistors. (A second configuration.)

The linear power supply circuit of the second configuration described above prevents the potential difference between the control terminals of the first and second output transistors from becoming equal to or larger than a predetermined value. It is thus possible to reliably suppress an overshoot in the output voltage caused by a delay ascribable to a resistor and a capacitor for phase compensation.

In the linear power supply circuit of the second configuration described above, the potential difference suppressor may include an operational amplifier, and the operational amplifier may output the control signal. (A third configuration.)

With the linear power supply circuit of the third configuration described above, it is possible to build the potential difference suppressor with a simple configuration.

In the linear power supply circuit of the third configuration described above, the operational amplifier may have an input offset voltage. The non-inverting input terminal of the operational amplifier may be connected to the control terminal of the first output transistor, and the inverting input terminal and the output terminal of the operational amplifier may be connected to the control terminal of the second output transistor. (A fourth configuration.)

With the linear power supply circuit of the fourth configuration described above, it is possible, with the input offset voltage, to easily prevent the potential difference between the control terminals of the first and second output transistors from becoming equal to or larger than a predetermined value.

In the linear power supply circuit of the fourth configuration described above, the operational amplifier may include: a first input differential pair transistor connected to the control terminal of the first output transistor; a second input differential pair transistor connected to the control terminal of the second output transistor; and a current mirror circuit configured to feed the first input differential pair transistor with a first current and feed the second input differential pair transistor with a second current as a mirror current of the first current. The input offset voltage may be generated at least either by using MOS transistors as the first and second input differential pair transistors and giving the MOS transistors different channel width-to-channel length ratios, or by giving the first and second currents different values. (A fifth configuration.)

With the linear power supply circuit of the fifth configuration described above, it is easy to set the input offset voltage exactly to the design value.

The linear power supply circuit of any of the first to fifth configurations described above may further include: a resistor (82) between the control terminals of the first and second output transistors; and a capacitor (83) of which one terminal is connected to the input terminal and of which the other terminal is connected to the connection node between the resistor and the control terminal of the second output transistor. (A sixth configuration.)

With the linear power supply circuit of the sixth configuration described above, it is possible to achieve phase compensation without a great increase in the circuit area.

In the linear power supply circuit of the sixth configuration described above, the capacitor may be a parasitic capacitor of the second output transistor. (A seventh configuration.)

With the linear power supply circuit of the seventh configuration described above, it is possible to more effectively suppress an increase in the circuit area.

In the linear power supply circuit of the sixth or seventh configuration described above, the capacitance value of the capacitor is higher than the capacitance value of a capacitance (CPD) between the first terminal, connected to the input terminal, of the output transistor and the control terminal of the first output transistor. (An eighth configuration.)

With the linear power supply circuit of the eighth configuration described above, it is easy to achieve phase compensation.

In the linear power supply circuit of any of the sixth to eighth configurations described above, the capacitor may include a capacitance different between a parasitic capacitance present between the first terminal, connected to the input terminal, of the second output transistor and the control terminal of the second output transistor. (A ninth configuration.)

11

With the linear power supply circuit of the ninth configuration described above, it is easy to adjust the capacitance value of the capacitor.

In the linear power supply circuit of any of the first to ninth configurations described above, the first and second output transistors may have different sizes. (A tenth configuration.)

With the linear power supply circuit of the tenth configuration described above, it is possible to make the currents through the first and second output transistors different in magnitude.

In the linear power supply circuit of the tenth configuration described above, the size of the second output transistor may be larger than the size of the first output transistor. (An eleventh configuration.)

With the linear power supply circuit of the eleventh configuration described above, it is possible to make the current through the second output transistor higher than the current through the first output transistor.

In the linear power supply circuit of any of the first to eleventh configurations described above, the output stage may be configured as a PMOS source-grounded circuit. (A twelfth configuration.)

With the linear power supply circuit of the twelfth configuration described above, it is possible to obtain a high voltage gain in the output stage.

According to another aspect of what is disclosed herein, a vehicle includes a linear power supply circuit of any of the first to twelfth configurations described above. (A thirteenth configuration.)

With the vehicle of the thirteenth configuration described above, it is possible to suppress an overshoot in the output voltage of the linear power supply circuit.

The invention claimed is:

1. A linear power supply circuit, comprising:
an output stage between an input terminal to which an input voltage is applied and an output terminal to which an output voltage is applied, the output stage including a first output transistor and a second output transistor connected in parallel with each other;

a driver configured to drive the first and second output transistors based on a difference between a voltage, which is based on the output voltage, and a reference voltage; and

a potential difference suppressor configured to suppress a potential difference between a control terminal of the first output transistor and a control terminal of the second output transistor,
wherein

the potential difference suppressor is configured to monitor a voltage difference between a first voltage at the control terminal of the first output transistor and a second voltage at the control terminal of the second output transistor and,

based on the voltage difference being equal to or larger than a predetermined value, output a control signal to control the first voltage and/or the second voltage at the control terminals of the first and second output transistors so as to reduce the potential difference between the control terminals of the first and second output transistors,

the potential difference suppressor includes an operational amplifier,

the operational amplifier is configured to output the control signal,

the operational amplifier is configured to receive an input offset voltage,

12

a non-inverting input terminal of the operational amplifier is connected to the control terminal of the first output transistor,

an inverting input terminal and an output terminal of the operational amplifier are connected to the control terminal of the second output transistor, and
wherein the operational amplifier includes

a first input differential pair transistor connected to the control terminal of the first output transistor,

a second input differential pair transistor connected to the control terminal of the second output transistor, and

a current mirror circuit configured to feed the first input differential pair transistor with a first current and feed the second input differential pair transistor with a second current as a mirror current of the first current, and

the input offset voltage is generated at least either

by using MOS transistors as the first and second input differential pair transistors, wherein the MOS transistors have different channel width-to-channel length ratios, or

by giving the first and second currents different values.

2. The linear power supply circuit according to claim 1, wherein

the first and second output transistors have different sizes.

3. The linear power supply circuit according to claim 2, wherein

the size of the second output transistor is larger than the size of the first output transistor.

4. The linear power supply circuit according to claim 1, wherein

the output stage is configured as a PMOS source-grounded circuit.

5. A vehicle, comprising the linear power supply circuit according to claim 1.

6. A linear power supply circuit, comprising:

an output stage between an input terminal, which is arranged to receive an input voltage, and an output terminal, which is arranged to provide an output voltage, the output stage including a first output transistor and a second output transistor connected in parallel with each other;

a driver configured to drive the first and second output transistors based on a difference between a voltage, which is based on the output voltage, and a reference voltage;

a potential difference suppressor configured to suppress a potential difference between a control terminal of the first output transistor and a control terminal of the second output transistor;

a resistor between the control terminals of the first and second output transistors; and

a capacitor of which one terminal is connected to the input terminal and of which another terminal is connected to a connection node between the resistor and the control terminal of the second output transistor.

7. The linear power supply circuit according to claim 6, wherein

the capacitor is a parasitic capacitor of the second output transistor.

8. The linear power supply circuit according to claim 6, wherein

a capacitance value of the capacitor is higher than a capacitance value of a capacitance between a first

13**14**

terminal, connected to the input terminal, of the output transistor and the control terminal of the first output transistor.

9. The linear power supply circuit according to claim **6**,
wherein

the capacitor includes a capacitance different between a parasitic capacitance present between the first terminal, connected to the input terminal, of the second output transistor and the control terminal of the second output transistor.

10. The linear power supply circuit according to claim **6**,
wherein

the first and second output transistors have different sizes.

11. The linear power supply circuit according to claim **10**,
wherein

the size of the second output transistor is larger than the size of the first output transistor.

12. The linear power supply circuit according to claim **6**,
wherein

the output stage is configured as a PMOS source-
grounded circuit.

13. A vehicle, comprising the linear power supply circuit according to claim **6**.
